UNITED STATES PATENT OFFICE.

AURION V. CHEVERS, OF PROVIDENCE, RHODE ISLAND.

MUSICAL INSTRUMENT.

SPECIFICATION forming part of Letters Patent No. 453,462, dated June 2, 1891.

Application filed February 7, 1891. Serial No. 380,590. (No model.)

To all whom it may concern:

Be it known that I, AURION V. CHEVERS, a citizen of the United States, residing at Providence, in the county of Providence and State 5 of Rhode Island, have invented certain new and useful Improvements in Musical Instruments; and I do hereby declare the following to be a full, clear, and exact description of the invention, such as will enable others skilled 10 in the art to which it appertains to make and use the same.

This invention relates to improvements in musical instruments, which will be hereinafter more particularly described and pointed out. 15 In the accompanying drawings, forming part of this specification, Figure 1 is a perspective view of the instrument. Fig. 2 is a sectional view of Fig. 1. Fig. 3 is a perspective view of a box to be used with the instrument. Fig. 4 is a perspective view of a glass lamp-chimney which may be used with the instrument.

a a are two oblong bulbs, which may be made of any suitable material, as metal, wood 25 ivory, glass, india-rubber, &c., which when placed within the mouth in proper position, by whistling over them, as one would upon the fingers, will produce a musical sound or modulated tone. After suitable practice a 30 person can play any tune and modulate the same by the breath and produce all the notes of a flute or similar musical instrument. This little device furnishes an excellent accompaniment to any other instrument. These bulbs 35 *a a* may be attached to rigid legs or stems having a joint at their junction similar to the legs of a pair of compasses, with a tightening-screw to secure the exact distance between the bulbs, (not shown in the drawings,) as different persons in practice adjust the bulbs at 40

different distances. I prefer the device as shown in the drawings, which represents a small flexible rod *B*, which is curved to bring the bulbs *a a* close together. The two ends *b' b'* are looped and wrapped around the stem, 45 as seen at *b'' b''*, Fig. 2. The bulbs *a a* are made of flexible india-rubber and are sprung over the loops of the rod *B*. The wire *b* is covered with an india-rubber tube *b'''*. A plain wire may be used and the bulbs may be 50 molded of hard rubber directly upon the straight ends of the wire and dispense with the loops. The same may be done when any hard material is used for the bulbs, as glass, &c.

In Fig. 3 is represented an ordinary box *c*, 55 such as a common cigar-box, in which a hole is made in one end. The bulbs may be inserted in the orifice, and the performer by lifting and closing the lid when he is whistling a tune can modulate the sound. 60

In Fig. 4 is represented a glass lamp-chimney *d*. The bulbs are similarly used in the large end, and modulation is produced by the hand on the small end.

The ends of the wire may be simply looped 65 and not twisted over, as shown in the drawings, so that the bulb which covers the wire may have an oval end.

I claim—

A mouth-organ consisting of two bulbs *a a*, 70 attached to the ends of an elastic stem *B*, whereby the two bulbs may be adjusted toward or from each other, substantially as and for the purpose described.

In testimony whereof I affix my signature in 75 presence of two witnesses.

AURION V. CHEVERS.
